UNITED STATES PATENT OFFICE.

WILLIAM H. ROSE, OF JERSEY CITY, NEW JERSEY.

CONTAINER.

1,361,618.

Specification of Letters Patent. Patented Dec. 7, 1920.

Application filed August 9, 1919. Serial No. 316,398.

To all whom it may concern:

Be it known that I, WILLIAM H. ROSE, a citizen of the United States, and residing at Jersey City, Hudson county, State of New Jersey, have invented certain new and useful 5 Improvements in Containers, of which the following is a specification.

This invention relates to containers having paper board bodies and the purpose of the invention is to securely connect a metal 10 top to the container with the least possible expense. Such containers are used in very large quantities for packing and shipping dry material and to some extent for liquids and it has been customary to supply the 15 cheapest grade with paper caps or ends, and the somewhat better grade with one or two metal ends, the metal being secured to the usual cylindrical body by crimping it on to or otherwise interlocking the metal and the 20 paper. It has heretofore required expensive machinery to attach metal tops to the paper or cardboard bodies and in the operation of attaching the tops the paper is so 25 mutilated that the top will not remain permanently attached unless a high grade and expensive paper or cardboard is used. By the present invention it is possible to secure a metal top of any approved type to a paste- 30 board body without mutilating or damaging the body in any way, the top serving to strengthen the body rather than to weaken it. Furthermore, the top can be attached to the body without any machinery other than 35 devices now commonly used for attaching labels. I accomplish this by perforating or otherwise cutting away the flange of the top to expose parts of the body of the receptacle and pressing the label through the perforations or openings in the top into contact 40 with the body whereby the top is securely locked to the body.

The top may be of any type desired. For instance it may have a central closure of the 45 "friction top" type, as shown in Figure 1 of the accompanying drawing, or it may be a perforated top for sprinkling substances, such as spices, talcum and the like. Any of the common kinds of tin or sheet metal tops 50 can be applied without expense for the application to the container, provided the flange of the top is perforated so that it may be interlocked with the body in the operation of pasting on the usual label.

55 The invention will be more fully described

in connection with the accompanying drawings in which:

Fig. 1 is a side elevation of a paper or pasteboard container having a metal top constructed and attached according to the 60 present invention, parts being shown in section;

Fig. 2 is an enlargement of a part of Fig. 1;

Fig. 3 is a side elevation of a top or cap 65 of modified form;

Fig. 4 is a similar elevation partly broken away of another form of the invention;

Fig. 5 is a side elevation partly broken away of still another form of the invention. 70

Referring to the drawings, 10 indicates the body of a cylindrical paper container which may be of any usual construction, and 11 indicates the bottom of the container which may be of paper having its 75 flange glued or pasted to the outside of the body. The top 12 is of sheet metal, preferably tin, and is provided with a flange 13 having a series of openings or perforations 14 therein for a purpose to be presently described. The circular part of the top may be of any usual construction, either a plain top or a perforated top for dispensing powdered material, or a removable disk 15 held by friction in the central opening in 80 the top 12, as shown in Fig. 1.

The flange 13 is cylindrical and adapted to closely fit the outer surface of the end of the body 10 and to lie parallel therewith, the wall of the body being exposed through 90 the openings 14. After the top is applied the usual label 16 is placed on the carton or container in the usual way, with paste, and portions of it extend through the openings 14 and adhere securely to the wall of the 95 container, thus locking the top to the body. It is well known that paste such as used to apply labels will not adhere strongly to tin or other smooth metal and that it will adhere strongly to paper. For this reason 100 a sheet metal top with an imperforate flange cannot be satisfactorily secured to the body by paste. Fig. 3 illustrates a modified form of cap having a flange 17 provided in its lower edge with dove-tailed openings 18. A 105 label applied in the manner above described will extend through the openings 18 and become securely connected to the body of a container, thus interlocking the top or cap to the container.

Fig. 4 illustrates a different form in which the openings 19 in the flange 20 are elliptical, the operation being the same as illustrated in Fig. 1. Fig. 5 illustrates a 5 paper carton or container 21 having a cap 22 provided with a flange 23, the flange having at its lower edge a bead or projection 24. In this case the paper label or cover 25 is pasted to the body 21 and projects over 10 the bead 24 engaging the flange 23 and while the paper will not adhere satisfactorily to the metal it will shrink in drying and be drawn tight over the bead 24, thus securing the metal cap to the body of the 15 container.

It will be apparent that the foregoing invention has many advantages over containers as at present manufactured. A tin top may be used having all or any of the 20 features common to tin tops on metal cans and it may be secured to a body of the cheapest paper stock that can be used for the special purpose in view without weakening or mutilating the paper stock and 25 without any machinery other than what is commonly necessary to attach the labels. In the use of metal tops on paper containers heretofore it has been necessary to include expensive machinery to attach the tops to 30 the containers and to have a variety of dies or tools to attach the tops to different sized containers, and by the present invention I am able to avoid this expense. It will be apparent that packages provided with these 35 improved tops can be filled before the tops are applied, thus providing an opening of the full diameter of the package for filling.

It will be seen that in each form of the device illustrated in the drawings the body 40 or wall of the container, and particularly that portion engaged by the flange of the top is straight and rigid and that the depending flange on the top is also straight so that the top is retained on the body prin-

cipally by reason of the engagement of the 45 wrapper with the body through the unobstructed openings in the flange or the interlocking of the wrapper and the flange.

Having thus described the invention what is claimed as new and desired to be secured 50 by Letters Patent is:

1. A container having a non-metallic body provided with a straight rigid portion and a metal top having a straight depending flange surrounding and closely fitting the 55 said straight portion of the body and lying parallel therewith, said flange having openings therein, and a wrapper pasted over the body and over the flange of the top, the top being secured to the body by portions of 60 the wrapper extending through the openings in the flange and adhering to the body.

2. A container comprising a cylindrical paper body having a straight rigid portion, a metal top having a straight depending 65 flange surrounding and closely fitting the straight portion of the body and lying parallel therewith, the said flange having unobstructed openings therein, and a covering 70 of paper surrounding the body and said flange and pasted to the body through the openings in said flange, for the purpose set forth.

3. A container comprising a cylindrical paper body having a straight rigid portion, a sheet metal top having a straight cylindrical depending flange surrounding and closely fitting the outer surface of the straight portion of the body and lying parallel therewith, said flange having unobstructed perforations therein, and a wrapper or label pasted to the body and having a portion overlapping the flange of the top and connected to the body through said 80 perforations.

In testimony whereof I affix my signature.

WILLIAM H. ROSE.
